UNITED STATES PATENT OFFICE.

MINERVA E. HAROLD, OF FLUSHING, NEW YORK.

ADJUSTABLE HEAD PROTECTOR.

Application filed July 31, 1925. Serial No. 47,342.

My invention relates to head protectors and more particularly to protectors of this class which are for individual wear, to be supported on the shoulders of the wearer and provided with a frame work carrying a canopy to more or less shield the head and upper portion of the body from the sun, heat, rain, snow or other atmospheric conditions. My invention still more particularly relates to devices of this character showing the construction of a shoulder saddle which may be removably fixed upon the saddle piece and its padded covering, with the shoulders by means of straps forming a fastening straps attached thereto. Part thereof arranged to surround the wearer's chest and having a framework vertically adjustable to different heights and laterally adjustable to different widths; the frame and the means by which the adjustment vertically adjustable framework carrying a relation of these end members is effected. Fig. 1 is a perspective view of my device, assembled for use, with a canopy covering supported on the shoulders of the wearer more clearly show the construction and assembly of certain parts. Fig. 2 is a front view, showing my assembly of the body and the upper portion of the device as mounted on the body of the wearer. Fig. 3 is a fragmentary view in section, showing the construction of a shoulder saddle which may be removably fixed upon the saddle piece and its padded covering, with the shoulders by means of straps forming a fastening straps attached thereto. Fig. 4 is a fragmentary view, in detail showing the construction of the transverse frame and the means by which the adjustment vertically adjustable framework carrying a relation of these end members is effected. Fig. 5 is a vertical sectional view, taken across the vertically adjustable framework on lines 5—5 of Fig. 4, showing in detail to shield the head and upper portions of the wearer's body from heat, rain or other elements.

One of the objects of my invention is, to provide a device of this character, which may be conveniently mounted on the shoulders and securely held in place by straps or other suitable means engaging the wearer's body, so that it may be readily removed when desired.

Another object is, to provide a device of this character which shall be adjustable vertically to different heights and likewise comprise a canopy holding framework adjustable to different widths.

Another object is, to provide a device of this character which has a canopy holding frame, to effect a secure holding of the canopy over its supporting top frame in all conditions of lateral adjustment thereof.

Another object is, to provide a device of this character which is of simple construction, of few parts, of light weight, of compact form, of rigid design and which, when worn, will afford protection from heat, rain and other atmospheric elements and at the same time offer no substantial obstruction to the vision in any direction and will permit an unimpeded use of the body and limbs of the wearer.

My invention consists in the particular combination, organization and arrangement of parts shown in the accompanying drawings, described in the specification and more particularly defined in the appended claims.

Referring to the drawings, in which like numerals of reference indicate corresponding parts, my device consists of a pair of preferably tubular standards 10, which extend upward the desired height and terminate at their lower ends in substantially semi-circular shaped saddle portions 11, which are preferably integral with the standard portions 10 and are adapted to be seated upon the shoulders of the wearer.

The saddle portions 11, are encased in a covering 12, which may be of leather, canvas, or other suitable material, such as will not readily conduct heat and which will serve as a means by which suitable padding 13 may be held around the ends and under sides of the saddle portions 11 in order to present a sufficiently resilient soft contact surface when the saddle portions 11 are adjustable for use. This padding may be of wool, cotton, cork, rubber or any suitable soft resilient material.

Attached to each end of the saddle portions 11, and the encasing cover 12, by means of rivets 14 or other suitable fastening means, are straps 15 and 16 that are suitably perforated to permit the saddle limbs of the wearer.

The straps 15 and 16 are engaged by buckles 17 and 18 and held therein. These buckles 17 and 18 are attached to the upper ends of the straps 19 and 20,

which latter are, on their opposite ends, securely fixed by rivets or by sewing or otherwise to a strap or belt 21, which is provided to encircle the wearer's chest at 5 a suitable point below the armpits. This strap or belt 21 is provided with a buckle 22 and usual perforations 23, so that it may be adjusted to any degree of tightness desired by the wearer.

10 Slidably mounted in the vertical tubular standards 10, I provide rod-like standards 24, which are detachable from the tubular standards 10 and which may be vertically adjusted in the tubular standards 10 to any 15 suitable degree. Set screws 25, threaded into the tubular standards 10 are adapted to engage the slideable standards 24 and lock them in adjusted position. The standards 24 are preferably of rod-like 20 formation, but may, if desired, likewise be made in tubular shape.

Carried upon the upper ends of the standards 24 and in fixed relation therewith, is a top framework, comprising opposite substantially parallel side portions 26 and 27, which are provided at their opposite ends with arms 28 and 29, bent at substantially right angles to the sides 26 and 27 and which lie in substantially the same plane, 30 and extend transversely from the sides 26 and 27 toward each other. The transverse end portions 28 and 29 each extend less than the entire distance between the sides 26 and 27. One pair of the transverse arms 29 35 forming these end portions are provided with bent up side members 30 and 31, which extend a suitable distance along the length of the members 29 and are so formed that they provide a case or channel in which the members 28 cooperating with the members 29, may be received and slide. The bent up side members 30 and 31 thereby serve as retaining guides to hold the members 28 in slideable relation to members 29. The bent up edges 30 40 and 31, at their adjacent edges are spaced apart so as to form a slot 32, running the length of the channel formed by these members 30 and 31, in which slot 32 the threaded pin or stud 33, fixed to each of the members 28, slidably travels. Mounted on the threaded stud or pin 33, adjacent the faces between which the slot 32 is formed, is a washer 34, which is engaged by a wing nut 35 threaded on the pin 33. This wing nut 35 being adjustable on the pin 33 may be tightened against the washer 34, so that the arm 28 45 may be clamped in the encasing channel portion formed by the sides 30 and 31 of the arm 29 and the arms 28 and 29 locked in any 50 position of adjustment by the operation of the wing nut 35 on the threaded stud 33.

Carried on the vertical standards 24, is a canopy carrying sub-frame, which comprises the canopy holding rod-like members 55 37 and 38, arranged substantially parallel to,

but below the side members 26 and 27 of the top canopy frame and forwardly and rearwardly extending arms 39 and 40, substantially integral with the rod-like members 37 and 38 and forming a truss-like framework 70 supporting the rods 37 and 38, the whole being carried by collars 41 and 42 slidably mounted upon the vertical standards 24. The collars 41 and 42 are provided with set screws 43, threaded therein and adapted to 75 engage the vertical standards 24 and lock the collars 41 and 42 in any desired position of vertical adjustment. A canopy 44 made of any suitable fabric, or material that will be of sufficient lightness in weight to be 80 desirable for its intended use and which is preferably waterproof, is securely attached to the rod-like members 37 and 38 on the opposite sides of the top frame formed by the side members 26 and 27 and the end members 85 28 and 29 and is stretched from the members 37 and 38 across the above described canopy holding frame. The canopy 44 may thereby be stretched tightly over the top canopy holding frame, by adjusting the 90 collars 41, 42 carrying the sub-frame, to the desired height upon the vertical standard 24. The canopy is thus tightly held against displacement by wind or otherwise and securely retained in its proper operative position to 95 shield the wearer from the sun, rain or other elements as intended.

The operation of my device is as follows:—

The vertical standards 10 are placed by 100 positioning the padded saddle pieces 11, with the straps 15 and 16 attached thereto, over the shoulders of the wearer. The belt 21 is then securely fastened in position around the body below the arm pits and the 105 saddle pieces 11 are securely drawn into place and adjusted by tightening the straps 15 and 16 in the buckles 18 and 17 attached to the straps 19 and 20. The vertical standards 24 are adjusted in the tubular vertical 110 standards 10 to the desired height, so that the canopy supporting framework, comprising the side members 26 and 27 and the end members 28 and 29, will be at the desired height above the wearer's head. The width 115 of the canopy supporting top frame may then be adjusted to the desired size, by sliding the end members 28 and 29 upon each other to the proper position and locking these members in adjustment by means of the 120 wing nut 35. The canopy may then be stretched tightly across and over the top canopy supporting frame, by sliding the collars 41 and 42, carrying the canopy holding bars or rods 37 and 38, to the desired position 125 along the vertical standards 24 and locking these collars and the canopy holding sub-frame in this position, by means of the set screws 43. The parts will then be assembled as intended for use and the device may be 130

conveniently carried or worn so that the wearer will be substantially sheltered from the elements and at the same time will be permitted free vision in all directions and 5 unobstructed use of the limbs and other parts of the body. The device may be readily removed by unfastening the belt 21 at the buckle 22 and, if necessary, the belt 16 and 20, or 15 and 19 may be unfastened or loosened at the buckles 18 and 17 respectively. When this is done the device may be removed by merely dismounting the saddle portion 10 from the shoulders.

That my apparatus may have no unnecessary weight, the standards and framework including the saddle pieces, may be made of aluminum, or any sufficiently light and strong metallic material or they may be constructed of any other suitable material for 15 instance of bamboo. The canopy may be made of water-proof, oiled silk, rubberized fabric or any other suitable material of sufficient durability to withstand ordinary use under the various conditions of climate or 20 weather in which my device may be employed.

By reason of the peculiar construction of my device, it is apparent that it may be readily disassembled and stored or carried in 30 a compact manner and in a minimum of space and that it may be readily and conveniently transported as a whole.

It will be obvious that I have provided means that may be conveniently attached to 35 the body of the wearer and readily detached therefrom, which will partially shield the wearer from the effects and action of the elements, which is adjustable in many of its parts, which is of durable and simple construction, which is light in weight, which 40 will not obstruct the vision or impede the use of the limbs or other parts of the wearer's body, which may be conveniently transported in assembled or disassembled condition, which is of few parts, of comparatively 45 cheap manufacturing cost, which has a high degree of efficiency for the purposes for which it is designed and which may have other advantages and results not 50 specifically herein set forth.

Although I have shown and described my invention in detail, I do not wish to be limited thereby, except as the state of the art and the appended claims may require, 55 for it is obvious that various modifications and changes may be made therein, without departing from the spirit and scope of my invention.

What I claim is new and desire to secure 60 by Letters Patent is:—

1. In a device of the character described, the combination of a laterally adjustable canopy carrying framework, standards to support said framework, means vertically 65 adjustable on said standards, adapted to

hold a canopy covering on said framework and means to detachably attach said supporting means to the body of the wearer.

2. In a device of the character described, the combination of a laterally adjustable 70 canopy carrying framework, means to lock said framework in a laterally adjusted position, means to support said laterally adjustable framework in vertically adjusted relation to said supporting means, means to 75 adjustably attach the supporting means in operative position to the body of a wearer, a canopy covering carried by said laterally adjustable framework and means connected to said canopy covering, vertically adjust- 80 able on said supporting means adapted to hold said canopy covering in operative relation to said laterally adjustable framework.

3. In a device of the character described, the combination of a laterally adjustable canopy carrying framework, means to lock 85 said framework in a laterally adjusted position, means to support said laterally adjustable framework in vertically adjusted relation to said supporting means, means to 90 adjustably attach the supporting means in operative position to the body of a wearer, a canopy covering carried by said laterally adjustable framework, means connected to 95 said canopy covering vertically adjustable on said supporting means, adapted to hold said canopy covering in operative relation to said laterally adjustable framework, and means adapted to lock said vertically adjustable canopy holding means in adjusted position.

4. In a device of the character described, the combination of a substantially rectangular shaped canopy carrying framework 105 formed in sections, adapted to permit lateral adjustment of said sections relatively to each other, means carried by one of said sections adapted to engage the other of said sections and lock said sections in adjusted relation, supporting standards fixed to said framework, a canopy covering carried on and spanning said framework, a sub-frame vertically adjustable on said standards connected to said canopy covering and adapted to hold said canopy covering in operative relation to said framework, means to lock 110 said sub-frames in adjusted positions, substantially tubular standards supporting said sub-frame carrying standards in vertically adjustable relation therewith, substantially semi-circularly shaped bases supporting said tubular standards and adapted to be carried on the shoulders of a wearer, and adjustable fastening means connected to said supporting bases adapted to engage the body of the wearer and hold said bases and framework carried thereon in operative relation thereto.

5. In a device of the character described, 120 the combination of substantially vertical 125

- 4
- standards detachably adjustable to the shoulders of wearer, a laterally adjustable framework supported on said standards in vertically adjustable relation therewith, 5 means to lock said framework in lateral and vertical positions of adjustment, sub-frames carried by said vertically adjustable framework and in vertically adjustable relation therewith, means to lock said sub-frames in 10 adjusted positions, a canopy covering spanning and carried by said laterally adjustable framework and connected to said sub-frames and adjustable in relation to said laterally adjustable framework by a vertical adjustment of said sub-frame.
6. In a device of the character described, the combination of a laterally adjustable top canopy carrying framework of a substantial rectangular shape, comprising a pair of 20 members forming the sides and ends of said frame, one of said members having channelled guiding means adapted to receive and hold the other of said members in laterally 25 slidable relation thereto, means carried by one of said members adapted to lock said pair of members in adjusted position and means connected to said canopy carrying framework adapted to support said framework upon the body of a wearer.
7. In a device of the character described, the combination of a top canopy carrying framework of a substantially rectangular shape comprising a pair of members forming the sides and ends of said framework, 30 one of said members having a channelled guiding means adapted to receive and hold the other of said pair of members in laterally slidable relation thereto, means carried by one of said members adapted to lock said pair of members in laterally adjusted relation, a canopy supported on and spanning said framework, vertically supporting members connected to said framework and adapted to support said framework in 35 operative position upon the body of a wearer and means vertically slidable upon said supporting framework connected to said canopy, adapted to adjust said canopy to said supporting framework independently 40 of the means to laterally adjust said canopy supporting framework.
8. In a device of the character described, the combination of a laterally adjustable canopy supporting frame, a canopy spanning said frame and adjustably supported thereon, means to support said canopy frame in vertically adjustable relation to said supporting means, means vertically adjustable on said supporting means adapted to effect the adjustment of said canopy to said canopy 55 frame, independently of the adjustment vertically of said canopy frame to said supporting means, and means to adjust said canopy frame laterally, independently of the adjustment of said canopy to said frame. 60
9. In a device of the character described, the combination of a canopy frame having its lateral longitudinal sides laterally adjustable in relation to each other, means to lock said sides in adjusted position, means to support said canopy frame in vertically adjustable relation to said supporting means, independently of means to effect the lateral adjustment of said canopy frame, a canopy carried on and spanning said canopy frame, 70 means carried on said supporting means connected to said canopy and vertically adjustable on said supporting means, independently of the vertical adjustment of said canopy frame and means adapted to operably support said supporting means on the 75 body of the wearer.
10. In a device of the character described, the combination of a canopy carrying framework, a canopy adjustably supported on said framework, means to adjust said canopy to said framework, and means to operably support said canopy framework supporting means on the body of the wearer, said canopy carried framework comprising a pair of 80 frame sections, one of said sections being provided with channel portions adapted to guide and receive the other of said sections, a threaded stud carried upon one of said sections and a nut in adjustable engagement 85 with said stud, adapted to engage the other of said sections and lock said frame work sections in adjusted relation.

Signed at the city of New York in the county of New York and State of New York 100 this 30th day of July, A. D. 1925.

MINERVA E. HAROLD.
